CLAIM

The ornamental design for a splint as shown and described.

DESCRIPTION

FIG. 1 is a bottom-rear perspective view of a splint, showing my design;

FIG. 2 is a top-rear perspective view thereof;

FIG. 3 is a top-front perspective view thereof;

FIG. 4 is a right side perspective view thereof;

FIG. 5 is a left side perspective view thereof;

FIG. 6 is a top view thereof; and,

FIG. 7 is a bottom view thereof.

The broken lines in the drawings depict portions of the design that form no part of the claim.
